United States Patent Office

Des. 199,156
Patented Sept. 15, 1964

199,156

TISSUE PAPER OR SIMILAR ARTICLE

Charles P. de Volpi, 109 Sunnyside Ave.,
Westmount, Quebec, Canada

Filed Feb. 15, 1963, Ser. No. 73,624

Claims priority, application Canada Aug. 22, 1962

Term of patent 14 years

(Cl. D59—2)

The figure is a plan view of a tissue paper or similar article, showing my new design. A design unit is enclosed within the dot and dash lines which unit is repeated in regular succession as indicated by the extensions beyond the unit boundaries.

I claim:

The ornamental design for a tissue paper or similar article, as shown and described.
